ASSEMBLY MACHINE

Robert M. Weigel, Seattle, Wash., assignor to The Boeing Company, Seattle, Wash., a corporation of Delaware
Filed Oct. 18, 1962, Ser. No. 231,333
10 Claims. (Cl. 29—203)

This invention relates to an assembly machine, and more particular to an assembly machine for aligning and inserting contacts into a connector such that the contacts are easily indexed and accurately placed to assure circuit integrity and constant contact reliability.

Indexing and inserting of contacts into a connector is presently done primarily by hand. Past experience has shown that an insertion path perpendicular to the connector end face is required to produce constant contact reliability, i.e., prevent bending of contact and the elimination of seal web damage. The present hand operation does not provide for ease of indexing and constant perpendicular contact insertion or control of the depth and force of insertion.

Much effort has gone into developing more efficient means of indexing and more effective methods of inserting the contacts, even to the use of expensive taped programming and tooling systems requiring protective devices which create a problem of obtaining experienced operators.

The instant invention has overcome the above mentioned disadvantages of the present known methods by providing a low cost machine that (1) is capable of accepting, indexing, and retaining any type of removable contact connector; (2) is capable of very accurate indexing of connector or insertion tool easily and quickly in any order; (3) can be actuated manually, semi-manually, or automatically with a camming master template; and (4) provides constant perpendicular contact insertion.

Broadly, the machine constitutes a master template and an indexing means comprising a first chuck and an indexing pin interconnected through an exaggerating pantograph. A second chuck is mounted for movement along its axis with the two chucks being oriented such that their axes remain parallel when the position of the first chuck is shifted by the action of the pantograph as the indexing pin is located in the various openings in the master template. A connector element and a contact insertion tool are mounted in said chucks to effect the assembly operation due to their relative motion as the second chuck is moved forward on its axis. While the operation may be either manual, semi-manual or completely automatic with proper control means, the mechanism assures that the contacts will always be inserted perpendicularly to the connector end face.

An object of the invention is to provide a device for inserting elements into a receiver.

A further object of the invention is to provide a means for quick and accurate alignment of assembly elements.

Another object of the invention is to provide a device for inserting contacts perpendicularly into a connector end face.

Another object of the invention is to utilize an exaggerating pantograph to magnify accuracy of indexing and maintain parallelism for perpendicular matching of assembly elements.

Another object of the invention is to provide a device for inserting contacts perpendicularly into a connector end face on a consistent insertion path which produces constant contact integrity.

Another object of the invention is to provide a device for inserting contacts into a connector end face on a perpendicular insertion path which produces constant

2

contact reliability that can be operated economically and effectively either manually, semi-manually or automatically.

These and other objects of the invention not specifically set forth above will become readily apparent from the accompanying description and drawings in which:

FIG. 1 is an isometric view of one embodiment of the invention;

FIG. 2 is an isometric view of another embodiment of the invention; and

FIGS. 3 and 4 show embodiments of the master template.

Referring to FIG. 1 the device is positioned on a work table or bench 1 and comprises template holder 2 secured to work table 1 by means such as studs 3. Removably attached to template holder 2 is a master template 4 having therein a plurality of index openings 5. Secured to work table 1 by studs 6 is an exaggerating pantograph consisting of linkage and lever means and generally indicated at 7. Exaggerating pantograph 7 comprises a support having upright portions 8, a first pair of linkage means 9 pivotably mounted at one end on shaft 10 which extends through uprights 8. A second pair of linkage means 11 is pivotably attached to the other end of linkage means 9 by a shaft 12 which extends through the ends of linkage means 9 and 11. A spring loaded indexing pin 13 is slidably mounted in the other ends of linkage means 11. Spring loaded indexing pin 13 is adapted to engage index openings 5 in master template 4. A pair of lever means 14 is pivotable mounted at one end thereof to linkage means 9. A control shaft 15 is attached through the other end of lever means 14. A third pair of linkage means 16 is pivotably mounted at one end on control shaft 15 and at the other end on linkage means 11. Control shaft 15 is secured at one end to a vertical reference stabilizer 17 operatively attached to table 1 at 18 which allows shaft 15 to move up and down or sideways but prevents said shaft from rotating. A chuck 19 is operatively attached to the end of shaft 15 opposite stabilizer 17, said chuck being designed to hold a receiver unit such as connector 20 which has an end face 21.

Secured to work table 1 by studs 22 is a tool chuck holder 23. Chuck holder 23 is provided with an aperture extending therethrough within which shaft 24 passes. Operatively connected to one end of shaft 24 is insertion tool chuck 25 which holds tool 25', said tool 25' being designed to hold an element such as contact 26 for insertion into connector 20 on a plane perpendicular to end face 21. The end of shaft 24 opposite to chuck 25 is threaded to provide for movement of depth adjusting nuts 27. Said depth adjusting nuts determines the depth of insertion of contact 26 into connector 20. Operatively attached to the threaded end of shaft 24 is a link 28 interconnecting shaft 24 with an insertion lever 29 which is pivotably mounted at one end on work table 1.

As stated above, accuracy is required in inserting contacts into the connector and with the prior art hand operation as speed increases accuracy decreases. Thus with the machine of FIG. 1 accuracy and speed is increased and the machine does not require an experienced operator. For each type of connector required, the holes on end face 21 are provided with small numbers to indicate the type contact to be inserted thus creating a problem in reading these small numbers. Therefore, a master template 4 is designed for each type connector and numbers are placed at each of the index openings 5 on the template to correspond with the numbers on the connector. The numbers on the template being much larger than those on the connector, exaggerated proportionate to pantograph, thus making them easy for the operator to read.

70

In operation of the FIG. 1 device, the operator merely inserts indexing pin 13 of the exaggerating pantograph 7 into the desired index opening 5 of master template 4. Movement of indexing pin 13 on template 4 causes a corresponding movement of connector chuck 19 to the desired location where a contact 26 is inserted thereinto by movement of lever 29, thus providing an efficient and effective method of inserting the contact into end face 21 in a constant perpendicular path.

Referring now to the FIG. 2 embodiment, the elements corresponding to those of FIG. 1 have been numbered accordingly. The primary difference between the FIG. 1 and FIG. 2 devices is that in FIG. 2, connector chuck 19 is secured to work table 1 by holder 30 and studs 31 while insertion tool chuck 25 is rotatably attached to exaggerating pantograph 7 and axially movable by lever 29. In FIG. 2, tool chuck 25 is attached to one end of shaft 32 which is operatively attached to lever means 14 of pantograph 7 for movement therewith. The other end of shaft 32 is threaded and provided with depth adjusting nuts 27. Lever 29 is pivotally mounted on a flange 33 extending from lever means 14 and is operatively connected to shaft 32 by link 28, whereby movement of lever 29 actuates tool chuck 25 as in the operation of the FIG. 1 device described above.

In operation of the FIG. 2 device, the operator positions indexing pin 13 in the desired index opening 5 of master template 4 which causes corresponding movement of tool chuck 25 through pantograph 7, thereby aligning chuck 25 with the desired hole in connector 20. Movement of lever 29 by the operator moves chuck 25 axially to insert contact 26 into connector 20, the depth of insertion being determined by adjusting nuts 27.

Manual axial movement of tool chuck 25 in either the FIG. 1 or FIG. 2 device can be replaced with power actuated means generally indicated by power actuator 34 which can be controlled by any well known electric, pneumatic or hydraulic system.

FIGS. 3 and 4 are two embodiments of master templates which constitute a plurality of openings set in a pattern corresponding to the desired positioning of contacts in the connector. For example, the operator would begin by placing the indexing pin in the opening of the template marked 1 and insert contact by lever 29 and subsequently move the indexing pin to each of the openings as numbered on the template and insert the desired contact in each of the corresponding holes of the connector. The openings of the templates of FIGS. 3 and 4 are interconnected by grooves to aid the operator in moving the indexing pin through the sequence. However, such grooves merely aid in increasing the operation speed and are therefore not necessary.

While the templates shown utilize a circular pattern, any pattern can be used to carry out the desired sequence of inserting the contacts into the connector. The pattern used will be determined by the number, size and location of the contacts to be inserted.

While not shown, a full automatic system for operating the indexing pin 13 and tool chuck 25 is within the skill of those familiar with the art. For example, initial movement of pin 13 would close a circuit to a magazine loading circuit for contact chuck 25 which upon completion of loading would energize a switch to operate power actuator 34 to move chuck 25 axially to insert contact 26 into connector 20. Means actuated by a predetermined movement of depth adjusting nuts 27 or other moveable units would reverse power actuator 34 and serially actuate means to move indexing pin 13 to the next opening in the master template, whereby the cycle will begin again.

It has thus been shown that the instant invention overcomes the drawbacks of the previous known methods of inserting contacts into a conductor while providing an efficient and effective device for inserting the contacts on

a constant perpendicular path with respect to the end face of the conductor, thereby producing constant contact reliability.

While particular embodiments of the invention have been illustrated and described, it will be obvious to those skilled in the art that various changes and modifications may be made without departing from the invention and it is intended to cover in the appended claims all such changes and modifications that come within the true spirit and scope of the invention.

What I claim is:

1. A device for aligning and inserting elements into a receiver comprising: means adapted for holding a receiver, means adapted for holding at least one element, exaggerating means for aligning said first and second named means in a predetermined position with respect to one another, and means adapted for perpendicularly inserting the element into an end face of the receiver.

2. A device as defined in claim 1 wherein said exaggerating means includes a master template and a pantograph having indexing means operatively positioned with respect to said master template.

3. A device as defined in claim 1 wherein said element holding means is moved axially by said last named means when said element is inserted into the receiver.

4. A device as defined in claim 1 wherein said last named means includes adjustable means for determining the depth of insertion of said element into said receiver.

5. A device for inserting elements into a receiver unit comprising: master template means having a plurality of index openings, an exaggerating pantograph including an indexing pin means, receiver unit holding means, element holding means adapted for holding at least one of the elements, means for axially moving said element holding means, whereby positioning of said indexing pin means in the desired index openings of the template means correspondingly aligns said receiver unit and said element in the desired position for insertion of said element into said receiver unit.

6. A device as defined in claim 5 wherein said receiver unit holding means is positioned with respect to said element holding means in accordance with movement of said indexing pin means.

7. A device as defined in claim 5 wherein said element holding means is positioned with respect to said receiver unit holding means in accordance with movement of said indexing pin means.

8. A device for aligning and inserting contacts into a connector comprising: master template means having a plurality of index openings, an exaggerating pantograph including an indexing pin means, first chuck means adapted for holding a connector, second chuck means adapted for holding at least one contact, means for axially moving said second chuck means, and means operatively connecting one of said chuck means with said exaggerating pantograph, whereby positioning of said indexing pin means in the desired index opening of the template means correspondingly aligns said first and second chuck means in the desired position for perpendicular insertion of a contact into an end face of a connector.

9. The device defined in claim 8 wherein said first chuck means is positioned with respect to said second chuck means in accordance with movement of said exaggerating pantograph.

10. The device defined in claim 8 wherein said second chuck means is positioned with respect to said first chuck means in accordance with movement of said exaggerating pantograph.
